PROCESS FOR IMPREGNATING CABLES

Russell Swale Vincent, London, England, assignor to Callenders Cable and Construction Company Limited, London, England, a British company

Application January 28, 1939, Serial No. 253,454
In Great Britain February 2, 1938

3 Claims. (Cl. 117—61)

This invention relates to an improved process for impregnating, drying, or treating cables or like articles in long lengths.

It is customary to treat paper insulated cables by a method which may be described as "batch working." In this method a coil containing a length of cable (or several lengths) is treated as a whole while stationary in a container by processes such as drying and impregnating. Each treatment for a batch necessarily finishes before another batch can enter the container and before another treatment for the same batch can begin.

It is the object of the present invention to provide an improved process whereby cable may be continuously treated for removal of gas and moisture or for impregnation or for the two purposes in successive operations. Further objects are to provide an improved inlet gland, to provide improved combinations of inlet and outlet sealing devices and to provide improvements in heating the cable. The invention specially contemplates the combination of a dry inlet gland with an outlet seal consisting of a barometric leg. The scope of the invention is defined in the appended claims.

In a preferred form of the invention the cable is passed into a zone of moderately reduced pressure in which it is partly dried, degassed and heated and then passed into a zone of higher vacuum where it is further degassed and dried. It may then be passed into a zone where impregnation is accomplished under vacuum, then into a zone where impregnation is accomplished under atmospheric or superatmospheric pressure, and finally into a one where it is cooled, preferably by passage in contact with cold impregnating liquid. Heating may be employed in the impregnating zones. Such heating may be accomplished by passing the cable through a casing which is externally heated, e. g. by means of steam.

It is also advantageous in addition to preheat the cable, i. e. to raise its temperature prior to its entry into a region of low pressure where degassing is carried out.

During its passage from one zone to another of different pressure, the cable passes through a pressure seal. This may consist in some cases of a barometric leg filled with liquid which may be surrounded by a heating means and may serve as a zone of treatment. Alternatively, it may consist of a dry gland.

The heating of the cable prior to its impregnation is necessary to remove gas and moisture from it or from its covering, e. g. a paper wrapping.

One manner of practising the invention will be described in greater detail with reference to the accompanying drawings, in which:

Fig. 1 is a diagrammatic elevation of a suitable plant.

Fig. 2 is a side sectional elevation of a suitable form of gland for use in the apparatus shown in Fig. 1, and

Fig. 3 is a diagrammatic sectional elevation of a form of electrical induction heater suitable for heating or preheating cables having metallic cores.

In Fig. 1 of the drawings, 1 is a sealed inlet box, 2 is an inlet tube for cable, 3 is a gland on tube 2, 4 is a preheater (such as that shown in greater detail in Fig. 3) on tube 2, 5 is a pulley in box 1, 6 is an up-run tube, 7 is a jacket for tube 6, 8 is a seal box connected to tube 6, 9 is a pulley therein, 10 is a connection from box 8 to a vacuum pump (not shown), 11 is a down-run tube connected to seal box 8, 12 is a jacket for tube 11, 13 is a gland at lower end of tube 11, 14 is a seal box connected to tube 11, 15 is a pulley therein, 16 is an up-run tube connected to seal box 14, 17 is a jacket for tube 15, 18 is a seal box connected to tube 15, 19 is a pulley therein, 20 is a connection from box 18 to a vacuum pump (not shown), 21 is a jacket therefor, 22 is an open liquid tank connected to tube 20, 23 is a pulley therein, 24 is another up-run tube, 25 is a jacket therefor, 26 is a collecting funnel surrounding the top of tube 24, 27 is a pipe connecting funnel 26 with tank 22, 28 is a gland on the bottom end of tube 24, 29 is a gland on the top end of tube 24, 30 is an inlet pipe to tube 24 for degassed impregnating fluid delivered by pump 31, 32 is an unenclosed pulley, 33 is a final down-run cooling tube, 34 is a jacket therefor, 35 is a collecting funnel on top of tube 33, 36 is an exit trough, 37 is a pulley therein, 38 is a pump, 39 is a pipe connecting trough 36 with pump 38 and 40 is a pipe connecting pump 38 with funnel 35. Inlets and outlets 41 are provided for heating and cooling fluids on jackets 6, 11, 15, 20, 24 and 33. 42 is a pump for conveying liquid from tank 22 through a degassifier (not shown) to a sealed storage vessel (not shown) for degassed impregnated medium, such as a mixture of 25% of rosin and 75% of heavy oil such as valve oil. The glands 3, 13, 28 and 29 may be of the type shown in greater detail in Fig. 2.

In Fig. 2, 51 is a flange, drilled at 52, for securing tube 53 against an apertured face. Tube 53 is also flanged at 54 forming with distance pieces 55 and back plate 57, the gland body. 56

are pillars secured to flange 54 and back plate 57 by nuts 68 and shoulders 59. Pillars 50 have inclined ends 60 provided with holes through which pass threaded strainers 61 provided with wing nuts 62 and springs 63 mounted between washers 64. Wires 66 are connected to the strainers 61 and to the flange 51 at 66. These wires pass through a hole in a disc of resilient material such as cellular rubber inserted in the gland as shown at 67. A plurality of wires 65 and associated strainers are arranged peripherally so as to enable the hole in the disc 67 to be enlarged uniformly. Each strainer may be associated with several wires, e. g. four.

In Fig. 3, 68 is the insulation and 43 is the conductor of a cable passing through a sleeve 69, which is of electrically insulating and heat-resistant material. This sleeve supports the copper solenoid 70, which is formed of rectangular section tube through which cooling water is passed from inlet 71 to outlet 72. 73 are connections to a source of high frequency current (not shown).

In the operation of the apparatus shown in Fig. 1 a partial vacuum is produced in tubes 6 and 11 by the pump (not shown) connected to pipe 10 and a high vacuum is produced in tubes 15 and 20 by the pump (not shown) connected to pipe 19. This causes liquid in tank 22 to rise in tube 20 and form a barometric seal column.

A paper-wrapped cable indicated diagrammatically by the line marked 43 is fed to the right hand side of the apparatus. It passes through gland 3, preheater 4, under pulley 5 and up tube 6, over pulley 9 and down tube 11. In tubes 6 and 11 it is partially dried and degassed by the moderate vacuum. Then it passes through gland 13, under pulley 44, up tube 15, over pulley 18 and down tube 20. In tube 15 it is further degassed and dried under high vacuum and in tube 20 it is impregnated while still under vacuum. From tube 20 it passes under pulley 23, through gland 28, up tube 24, where it is impregnated under superatmospheric pressure, through gland 29, over pulley 32, down tube 33 where it is cooled by passage through cold impregnating liquid, under pulley 31 and out of trough 36 at the left hand side of the apparatus. The pulleys serve to guide the cable through the tubes but some or all of them may be driven to assist the passage of the cable through the apparatus.

The height necessary for tube 20 depends upon the density of the impregnating liquid. In general, a height of about 40 feet is required to enable an adequate degree of vacuum to be employed. The up-run and down-run tubes have their internal diameter only slightly larger than the maximum external diameter of the cables to be treated in the apparatus. In this way good heating efficiency is assured and it is possible to maintain an adequate head of cool liquid in tube 33 without circulating an undue amount. If it should happen that the cable treated has a much smaller diameter than tube 33, it may be desirable to provide a gland at the lower end of this tube.

The pressure maintained in tube 24 may be 40 lbs. per square inch. At this pressure the amount of liquid leaking through glands 28 and 29 is not great. That leaking through gland 28 collects directly in tank 22; that leaking through gland 29 collects in funnel 26 and runs thence through pipe 27 into tank 22.

In the drawing six tubes are shown. Further tubes may be provided for the preliminary degassing, for the degassing and drying, for the impregnation under vacuum, for the impregna-

tion under pressure, for an impregnation at atmospheric pressure or for cooling, if desired.

In the form of the invention described above, the preheating is effected by causing the cable to pass through the field of a solenoid, to which high frequency current is fed, so that the heating is accomplished by the eddy currents induced in the conductor of the cable after the manner of an induction furnace. The method of heating may also be used in the degassing and/or drying and/or impregnation. Other methods of heating and/or preheating may be used of which the following are examples:

(1) The cable may be heated by causing the metallic core to act as a conductor for an electric current, which may conveniently be induced in it by surrounding a portion of the cable with a coil through which intermittent or alternating current is passed, one or both ends of the cable being earthed.

(2) The capacitative effect of the cable may be taken advantage of by causing the metallic core to form one plate of a condenser of which the other plate is earthed, and inducing a current in the core by placing it in the field of a coil through which high frequency current is passed.

(3) The cable may be passed closely adjacent to a surface which is caused to radiate heat at a wave-length which the paper or other coating will transmit.

(4) The cable may be passed through a gaseous medium which will transmit the heat from an adjacent heated surface by convection.

(5) The cable may be brought into direct contact with a preheated gaseous medium, e. g. hot air.

(6) The drum or the like from which the cable is unwound before passage through the impregnating machine may be surrounded by a casing which is heated in any convenient manner or through which a hot gaseous medium is passed, to heat the whole mass of the cable.

Methods (4), (5) and (6) are particularly suitable for preheating the cable, while the other methods are suitable not only for preheating the cable, but for heating it during its passage through the apparatus shown in Fig. 1. Those methods which depend upon any form of electrical induction will, however, require a careful choice of suitable materials for the casing through which the cable is passed during its treatment.

In place of the gland shown in Fig. 3, other forms of glands may be used.

One such other form of gland may be constituted by a ring of resilient material such as rubber of a suitable size to press upon the cable which is passed therethrough. Such ring may have metal insertions to give greater rigidity and if desired may also have an outer reinforcement of thin metal strip or wire arranged, for example, in the form of a spiral. Such ring is arranged to abut against a rigid face on the side remote from that to which the cable is fed.

Another form of gland which may be used in practising the present invention is constituted by a sleeve of resilient material such as rubber, arranged in the form of a double cone which fits snugly upon the cable at its point of minimum cross section. This may be pressed upon the cable during the passage of the cable therethrough by the prevailing pressure of the surrounding atmosphere, or may be mounted in a

closed casing whereby any desired fluid pressure may be applied to the exterior.

Another form of gland which may be employed in practising the present invention consists of a hollow sleeve loosely packed with small solid spheres made of material which is inert to atmospheric influences or to the influence of any materials with which it may come into contact. Thus, small glass balls may be used. The sleeve is arranged to provide just sufficient clearance to permit the cable to pass therethrough, and the free movement of the spherical objects allows them to pack themselves closely around the cable. The spheres are preferably as small as possible, but must be sufficiently large not to permit their escape or jamming between the apertures in the sleeve and the cable.

Another form of gland which may be employed in practising the invention is constituted by an assembly of pairs of plates having concave cut-out portions adapted to press a little upon opposite sides of the cable. Such an assembly of plates may be constituted by two pairs of plates arranged to press together at right angles to one another, presenting an aperture after the manner of an iris diaphragm. The edges of the plates which contact with the cable may be suitably rounded to eliminate friction, and to obviate damage to the cable. More than two pairs of plates may constitute the assembly, if desired, and the elements of each pair may be pressed together by spring means or by gravity.

A further form of gland which may be employed in the present invention is constructed after the manner of a labyrinth such as is employed in conjunction with steam turbines. One form of such a labyrinth could, for example, consist of an elongated sleeve of metal which has been partially collapsed by known means, so as to produce a bellows form of such internal diameter that the cable will just pass through with a small clearance. A succession of annular spaces is thereby provided along the sleeve which assists in preventing the passage of air or gas from the zone of high pressure on one side to the zone of low pressure on the other side.

The dry glands above described are suitable for use not only on the inlet or outlet of a cable treating machine, but for use at the boundaries of zones of different pressure. By arranging for the cable to pass through successive zones of diminishing or increasing pressure, no undue load is placed on any gland since it is required merely to prevent undue leakage between zones which may not differ very considerably in pressure.

10 The invention is of particular value for the treatment of electric cables, but is not limited thereto since it can be used, for example, for the treatment of cords or ropes.

It will be apparent, however, that not all the 13 forms of heating described can be employed for treating materials which have not got metallic cores.

I declare that what I claim is:

1. A method of treating insulated cable in continuous lengths which comprises continuously 20 passing the cable between surfaces engaging the cable by dry friction in vacuum-sealing relationship into an evacuated space and out of said space through a liquid seal of impregnating composition, and subjecting the cable to preliminary heating before its entry into said evacuated space.

2. A method of treating insulated cable in continuous lengths which comprises continuously 30 passing the cable between surfaces engaging the cable by dry friction in vacuum-sealing relationship into an evacuated space and out of said space through a liquid seal of impregnating composition, and electrically heating the cable before 35 its entry into said evacuated space.

3. A method of treating insulated cable in continuous lengths which comprises continuously passing the cable between surfaces engaging the cable by dry friction in vacuum-sealing relationship into an evacuated space and out of said space through a liquid seal of impregnating composition, impregnating the cable in vacuo, and 40 continuously impregnating the cable with a liquid composition under pressure after said impregnation in vacuo.

RUSSELL SWALE VINCENT.
